(57) **CLAIM**

We claim the ornamental design for an electronic board, as shown and described.

DESCRIPTION

FIG. 1 is a front perspective view of an electronic board of the present invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged front perspective view of the claimed portion;

FIG. 9 is an enlarged front view of the claimed portion;

FIG. 10 is an enlarged right side view of the claimed portion; and,

FIG. 11 is an enlarged bottom view of the claimed portion.

The broken line showing of electronic board is included for the purpose of illustrating environment and forms no part of the claimed design.
